UNITED STATES PATENT OFFICE.

WILLIAM C. ARMSTRONG, OF SPRINGFIELD, OHIO.

GRATE-BAR.

1,169,107.

Specification of Letters Patent. Patented Jan. 25, 1916.

Original application filed May 20, 1912, Serial No. 698,366. Divided and this application filed November 2, 1914. Serial No. 869,749.

To all whom it may concern:

Be it known that I, WILLIAM C. ARMSTRONG, a citizen of the United States, residing at Springfield, in the county of Clark 5 and State of Ohio, have invented certain new and useful Improvements in Grate-Bars, of which the following is a specification, reference being had therein to the accompanying drawing.

This invention relates to grate bars, such as are used in the manufacture of grates for furnaces and the like, and is a division of an application for patent filed by me May 20th, 1912, Ser. No. 698,366.

The object of the invention is to provide a grate bar of superior strength and durability, and one on which the effects of the heat will be comparatively small.

To this end it is a further object of the invention to provide the grate bar with truss-like depending walls in which the metal is so disposed as to give the greatest strength at the points at which it is most needed, and which arrangement also serves 25 to provide an air passage through the grate bar; and also to taper the fingers of the grate bar both longitudinally and vertically and to so form the grate bar as to reinforce the fingers at their point of connection with 30 the body of the grate bar.

In the accompanying drawings, Figure 1 is a perspective view of a portion of a grate made up of grate bars embodying my invention; Fig. 2 is a detail view of a portion of 35 one of the grate bars showing the manner of mounting the same and the lengthwise taper of the fingers; Fig. 3 is a similar view with the grate bar in its normal position and showing both the vertical and the 40 lengthwise taper of the fingers; and Fig. 4 is an end elevation of a grate bar embodying my invention.

In these drawings I have illustrated one embodiment of the invention, and have shown 45 the same as embodied in each of a plurality of grate bars, indicated by the reference numeral 1, each of which is provided at its opposite ends with trunnions 2 which rest in bearings 3 in the upper edges of 50 frame members 4, thus pivotally supporting the several grate bars. Each grate bar is provided on its opposite sides with laterally projecting teeth or fingers 5, the alternate fingers of each grate bar being of 55 different length and the short fingers of

one grate bar being opposite the corresponding long fingers of the adjacent grate bars. The axes of the adjacent grate bars are spaced apart such distances that when said grate bars are in their normal positions their fingers will interlock or overlap so as to form a continuous flat surface to support the fuel. To increase the strength of the grate bars without materially altering the clearance between them I 60 prefer to taper the fingers lengthwise, as clearly shown in Fig. 2, and if desired they may also be tapered from the top toward the bottom, as shown in Fig. 3. The lengthwise taper gives an increased amount of 65 metal at the base of the finger where, of course, the greatest strain is imposed upon the finger. To further strengthen the finger at its point of connection with the grate bar and to facilitate the casting of the grate 70 bars I prefer to form round corners at the juncture of the fingers with the body of the grate bar, these corners constituting fillets which not only greatly reinforce the fingers 75 because of their shape, but this shape also 80 enables a stronger casting to be had, as it is difficult to make a satisfactory casting with a sharp corner. Each individual grate bar may be rocked about the axis of its trunnions to agitate the fuel and remove 85 therefrom cinders, clinkers and the like. To enable this rocking movement to be accomplished, one of the lateral fingers 5 of each 90 grate bar has a depending portion 6, and a connecting bar 7 is pivotally connected with the depending portion 6 of each grate bar, so as to cause the several grate bars to move in unison. An actuating bar or rod 8 is connected with the connecting bar 7 and extends to a suitable point, where it may be 95 provided with any suitable means for imparting rocking movement to the grate bars, 100 such means being fully shown and described in the above-mentioned application.

Each grate bar is provided with longitudinally depending walls or ribs 9, which are spaced apart and which form between themselves a chamber 10, communicating at its upper edge with a series of openings or slots 11 extending through the top wall or 105 body portion of the grate bars. This construction provides for a free circulation of air from the ash pit, through the body of the grate bar to the fuel, thus not only affording a better draft for the fire but tending to cool 110

the grate bar and minimize the effect of the heat thereon. The depending ribs 9 give a truss-like support to the body of the grate bar, thereby greatly strengthening the same.

5 In order that the grate bar may be reinforced at the points where the greatest strength is needed the two depending ribs are thickened at the lower edges, as shown at 12. I prefer also to thicken the ribs at their upper
10 ends where they merge into the body portion of the grate bar. Consequently, I have here shown the two ribs as having their inner faces concaved, thereby thickening the upper and lower edges thereof and reducing the thickness of the central portion thereof.

It will be apparent from the foregoing description that the grate bar thus produced has great strength and durability, that the effect of the heat thereon will be comparatively small, and further, that the construction which brings about these advantages is such as to enable the grate bar to be readily manufactured, thereby enabling it to be produced at a relatively low cost.

30 While I have shown and described one embodiment of my invention, it will be understood that this has been chosen for the purpose of illustration only, and that I do not wish to be limited to the details shown and described, as various modifications will occur to one skilled in the art.

Having thus fully described my invention, what I claim as new and desire to protect by Letters Patent, is:

1. In a grate bar, a substantially inverted U-shaped body portion comprising a horizontal, fuel-supporting surface and depend-

ing spaced apart ribs projecting from the longitudinal edges of said horizontal surface, said ribs being of increasing thickness from their central portions toward their lower edges.

2. In a grate bar, a substantially inverted U-shaped body portion comprising a horizontal, fuel-supporting surface and depending spaced apart ribs projecting from the longitudinal edges of said horizontal surface, and said ribs being thickened at their upper and lower portions. 45 50

3. In a grate bar, a body portion to support the fuel, having laterally extending fingers and also having truss-like ribs extending downward from said body portion, arranged longitudinally of said body portion and spaced apart to form a chamber between them, said ribs being thickened at their upper and lower edges. 55

4. In a grate bar, a substantially inverted U-shaped body portion comprising a horizontal, fuel-supporting surface, depending spaced apart ribs projecting from the longitudinal edges of said horizontal surface, a series of fingers projecting from each side of said body portion, the alternate fingers of each series being of different lengths, and said fingers being tapered from the body of the bar toward their ends. 60 65

In testimony whereof, I affix my signature
in presence of witnesses.

WILLIAM C. ARMSTRONG
